UNITED STATES PATENT OFFICE

JOSEPH H. HOERN, OF SAGINAW, MICHIGAN, ASSIGNOR TO WILCOX-RICH CORPORATION,
OF DETROIT, MICHIGAN, A CORPORATION OF MICHIGAN

METHOD OF MAKING TAPPETS

Application filed June 14, 1930. Serial No. 461,234.

This invention relates to valve tappets and their method of manufacture.

Heretofore in the manufacture of tappets for internal combustion engines, especially 5 tappets that require to be light on account of their use in high speed engines, it has been customary to first make a one-piece tappet by cutting the stem and head from a bar of steel, then to make the stem tubular by boring 10 a hole through it lengthwise so as to leave only a thin wall or tubular stem. The tubular stem was then plugged at the head end of the tappet by a tightly fitting steel plug and finally the working face of the tappet head 15 was built up by puddling cast iron in a thin layer over the working face of the tappet and over the inserted steel plug.

My invention relates to tappets of this general character, and the improvement is found 20 in a novel method and structure whereby I have overcome certain disadvantages that were inherent in the above described earlier method. One of the inherent disadvantages referred to was that after the tight-fitting 25 steel plug had been inserted in the tubular stem and the cast iron face was being puddled into place gases were liberated at the joint between the steel plug and the wall of the tappet bore, and these gases escaped 30 through the metal that was being puddled, so that imperfections were frequently found in the structure of the puddled iron tappet face around the periphery of the steel plug. This resulted in an undesirable proportion of 35 rejects. The object of my present invention, as already stated, is to overcome this defect and to produce a tappet of the same general construction and characteristics as were produced by the former method, but to avoid the 40 disadvantages above mentioned that necessarily included the use of such a plug.

The means by which I attain the above-mentioned objects and the method of procedure in its manufacture will now be explained.

In the drawing Fig. 1 is a longitudinal sectional view of a tappet embodying my improvement.

Fig. 2 is a face view of the same. 50 Numeral 1 indicates the tubular thin walled

tappet stem and 2 is a mushroom head integral with the stem, the face of the head being preferably recessed, as at 3, to provide a receptacle for the mass of puddled metal that constitutes the working face of the tappet. 55

My invention provides the plug for the end of the tubular stem 1 in the following manner:

A slug 4 of metal of any suitable form and length is fixed into the bore of the tubular stem 1 near its head end and is held there by press fit or otherwise. The cavity 5 thus formed at the end of the tubular stem is then filled with a button-like mass 8 of puddled metal, preferably mild steel. The hot metal becomes welded to the walls of the cavity 5 and to the face of the slug 4 and the cavity is filled up practically flush with the surface of the tappet head 2. Finally metal such as cast iron is added, by puddling, to the face 65 2a of the tappet head 2 so as to cover it and 70 also to cover the end of the button 6 of puddled metal.

It has been found in practice that the button 6 having been fused or puddled into place and backed by the slug 4 avoids the formation 75 of gas when the metal working face element 7 of the tappet is thereafter puddled into place. No gases can arise from between the plug and the wall of the stem, as in the earlier structures referred to and consequently the 80 puddled iron working face 7 is without the defects which were heretofore frequently found in a face which was puddled in place directly upon a metal plug which was inserted 85 in the stem as a backing.

By the means above described I have provided a simple and inexpensive method of applying a cast iron puddled face to the head of a thin walled tubular tappet and am enabled to secure uniformly satisfactory results, 90 so that the present method is well adapted for the manufacture in mass production of tappets of the kind described.

Having thus described my invention, what I claim and desire to secure by Letters Patent is:

The method of applying to a tubular tappet stem a face element devoid of imperfections comprising fixing a slug of metal in the bore of the stem near an end thereof to present a 100

cavity within the stem, depositing on said slug
within the cavity a mass of fused metal and
welding the same to the slug and to the walls
of the stem, so as to seal said slug gas-tight
5 to the stem, and thereafter applying to the
said deposited mass an additional quantity
of fused metal and shaping the same to form
said face element.

In testimony whereof, I affix my signature.
JOSEPH H. HOERN.
